SAND SUCKER APPARATUS

Ambrose L. Cox, Oildale, Calif.

Application October 4, 1938, Serial No. 233,277

6 Claims. (Cl. 166—19)

My invention relates to sand sucker apparatus for use in pumping sand and fluid from oil wells.

Among the important objects of the invention, are to provide a compact, readily portable, apparatus of this character in which vibration in operation is reduced to a minimum so that in action it will not break down nor disturb formations of oil sand behind the well casing.

Other objects are to provide apparatus for the purpose above set forth which is economical both as regards manufacture and upkeep, durable, easily assembled and disassembled, capable of high speed operation and positive action as regards dumping and which does not require washing of the sand chamber to free the same from sand, or fluid, as is necessary in present day apparatus of this character.

Still another object is to provide improved dumping means for use with sand sucker apparatus.

Other and subordinate objects are also comprehended by my invention, all of which, together with the precise nature of my improvement, will become apparent when the following description and claims are read with reference to the drawings accompanying and forming part of this specification.

In said drawings:

Figure 1 is a longitudinal sectional view through a sand sucker apparatus constructed in accordance with the present invention, the dumping section being omitted.

Figure 2 is an enlarged sectional view through the lower pressure relief valve shown in Figure 1.

Figure 3 is an enlarged sectional view through the plunger valve taken as indicated by the line 3—3 of Figure 1.

Figure 4 is an enlarged sectional view through the upper pressure relief valve shown in Figure 1.

Figure 5 is a fragmentary view in side elevation of the dump section and dump cage.

Figure 6 is a view in side elevation of the dump cage proper, the view being taken at a right angle to Figure 5, and

Figure 7 is a view in longitudinal section of the dump section with the key positioned therein.

Referring to the drawings by numerals, the sand sucker apparatus of my invention comprises a pump 1 of the type to be dropped into the well casing (not shown) and pulled out of said casing under operation of the usual operating mechanism with which well drills are equipped for such purposes and which being well known need merely be mentioned in passing.

The pump comprises an outer tubular section 2 of suitable length having externally threaded upper and lower ends 3 and 4, for a purpose presently seen, and an inner tubular shorter section 5 of relatively smaller diameter secured in the upper end of the outer section 1, axially thereof, and spaced therefrom by a cylindrical head casting 6 having a tubular lower skirt 7 threaded onto the upper end of the inner section 5 and seating on the upper end of the outer section 2, and a coupling sleeve 8 threaded on said skirt 7 and onto the upper end 3 of said section 2. An annular spacer 9 is interposed between the lower end of the inner section 5 and the outer section 2.

The head casting 6 is bored axially, as at 10, to receive a sliding plunger rod 11 vertically reciprocable therein, the bore 10 having a lower flaring end 12 and the plunger rod 11 an enlarged lower end 13 beveled, as at 14, to fit into and close said flaring end for a purpose presently referred to.

Suspended from the end 13 of plunger rod 11 is a plunger 15 comprising an upper cage 16 secured to the end 13 by an upper socket 17 on said cage threaded onto a stud depending from said end 13 of the plunger rod 11. The lower end of the cage 16 terminates in a nipple 18 having a circular seat 19 in the upper end thereof for a ball valve 20, said nipple having a reduced lower end 21 threaded into the upper end of a plunger tube 22 on which is mounted in any suitable manner, as shown for instance in Figure 3, a plurality of vertically spaced apart fibre suction cups 23 fitting into the inner section 5 of the pump.

At a suitable point below the lower end of the inner section 5, the outer section 2 has mounted thereon a lower relief valve 24 comprising a rod-like valve casing 25 extending diametrically of said section 2 with its opposite ends suitably anchored in said section and provided with a central vertical port 26 for the passage of fluid therethrough, chambers 27 in its respective outer ends and a pair of axial ports 28 extending from the port 26 to the chambers 27, respectively. The chambers 27 are closed by a pair of tubular screw plugs 29 threaded into the outer ends thereof and said chambers house a pair of ball valves 30 and 31 interposed between the said plugs and valves and urging the latter against suitable seats 32 in the chambers 27, whereby said valves 30 normally close the ports 28. The screw plugs are provided with openings 33.

communicating between the chambers 27 and the exterior of the outer section 2. The head casing 6 forms the housing of an upper relief valve, said casing being provided with a pair of diametrically opposite, longitudinally extending through bores 33 therein having reduced lower ends 34 opening into the upper end of the inner section 5 of the pump 1 and normally closed by a pair of upwardly opening ball valves 35 urged into closing position by a pair of coil springs 36 interposed between said valves 35 and tubular screw plugs 37 threaded into the upper end of said bores 33.

At the upper end of the plunger rod 11 is a bail member 38 having a lower weighted end 39 threaded onto said rod.

The bail member 38, as will be understood, is designed for the attachment thereto of the beforementioned operating mechanism (not shown).

20 The pump 1 is designed for the attachment thereto of a bottom dump or bailing section 40. The dump section 40 is preferably of the type comprising an upper tubular member 41 threaded at its upper end onto end 4 of the outer section 2 of said pump, an inner tubular member 42 extending through and below member 41 and having an externally flanged upper end 43 rotatably mounted on an internal shoulder 44 provided in the upper end of member 41 and against which said flange is held by the lower end of section 2, a lower outer tubular member 45 threaded onto the lower end of the member 42 and having diametrical slots 46 extending from its lower end upwardly for a suitable distance, a pair of longitudinally extending discharge ports 47 and 48 formed in the lower ends of the members 41 and 42, respectively, for movement into and out of registration under relative rotation of said members, and a valve unit fitted into the lower end of the member 42 below said ports comprising a sleeve 49 clamped to the member 42 by means of a base flange 50 thereon interposed between the lower end of said member 42 and an internal shoulder 51 on the lower tubular member 45, said sleeve having an upwardly opening flap valve pivoted thereto for opening and closing the same. A transverse pin 53 extending through members 45, 42 and sleeve 49, prevents said members from working loose.

50 The dump section 40 is designed for use with a dump cage and key as follows.

The dump cage 54 has the form of a somewhat cylindrical pedestal provided with legs 55, a base flange 56 by means of which it may be bolted, as at 57, to the rig platform 58, an upper end flat head 59 axially bored at 60 for the insertion of the lower tubular member 45 of dump section 41 therethrough, and a bar-like transversely extending support 61 for said member 45 suspended in diametrically opposed slots 62 in the cage 54 for vertical movement and by means of a pair of tension springs 63 pivotally connected at one end to laterally extending lugs 64 on the head 59 and having their opposite ends suitably connected to said support 61. A pair of stop pins 65 extending through said support 61 on opposite sides of the cage 54, respectively, limit endwise play of said support 61.

70 The support 61 has upstanding therefrom a flat key member 66 adapted to fit loosely into the beforementioned slots 46 provided in the lower member 45 of dump section 40 and for a purpose presently seen.

75 Referring now to the operation and use of the invention, the pump 1 is lowered into the well

casing by dropping the same therein. Under the weight of the pump sections 2 and 5 and the head casting 6, these parts gravitate downwardly relative to the plunger rod 11 so that the beveled end 12 of bore 10 is closed by a part 14 of said plunger rod and the pump plunger 15 is located in the upper part of the inner section 5 of said pump. When the outer section 2 strikes bottom, the pump plunger 15 is reciprocated in a manner which will be understood to draw sand and oil, or other fluid in the well, into the inner section 5 below said plunger 15. Under the downstrokes of the plunger 15 the lower relief valve 24 opens, in a manner which will be understood, and under upstrokes of said plunger the described upper relief valve similarly opens, the ball valve 20 under downstrokes of said plunger opening to permit air to pass through said plunger and escape by way of the upper relief valve as will be clear. As will be understood, opening of the ball valve 20 provides for trapping air between the plunger 15 and head casting 6 to be discharged on the upstroke of said plunger. Consequently, air is positively removed from below the plunger 15 thereby making dumping of the sand which is accumulated in the pump much easier to accomplish than with other types of pumps.

The sand and oil, or other fluid, are drawn upwardly past the lower relief valve 24 and through the port 26 thereof.

When it is desired to dump, or bail out, the pump, the latter is withdrawn from the well casing and the dump section attached to the lower end of the outer section 2 of said pump in the manner already described. The pump 1 and said section 40 are then maneuvered into a position over the dump cage 54 and the lower member of section 40 dropped into the aperture 60 and turned until the slots 46 thereof are in a position to receive the key member 66 whereupon the whole device is lowered onto the support 61. In this position of the parts, the lower member 45, the inner member 42 and the sleeve 49 of the dump section 40 are held stationary by said key so that by turning the pump 1 the section 41 of the dump section 40 may be rotated to bring the slot 47 thereof into registration with the slot 48 of member 42 whereupon the pump 1 may drain through the dump section 40 in a manner which will be understood without further explanation. In the attached position of the dump section 40, the flap valve 49 prevents escape of the contents of the pump 1 until the ports 47 and 48 are in registration.

The foregoing will, it is believed, suffice to impart a clear understanding of my invention without further explanation.

Manifestly the invention, as described, is susceptible of modification without departing from the inventive concept and right is herein reserved to such modifications as fall within the scope of the subjoined claims.

What I claim is:

1. In a sand pump for sumping oil wells, a tubular casing adapted to be lowered into the well, a head casting threaded onto the upper end of said casing and provided with a central bore, a plunger rod slidable in said bore for vertical reciprocation in said casing, a pump plunger secured to the lower end of said rod for reciprocation therewith and having an axial port extending therethrough, a ball valve mounted in the upper end of said plunger, and upper and lower pressure valve units in the lower end of said casing and in said casting, respectively, the upper

65

70

75

- unit opening outwardly under compression created by the upstroke of said plunger, and the lower unit opening outwardly under compression effected by the downstroke of said piston.
6. 2. In a sand pump for sanding oil wells, a tubular casing adapted to be lowered into the well, a head casting threaded onto the upper end of said casing and provided with a central bore, a plunger rod slideable in said bore for vertical reciprocation in said casing, a pump plunger secured to the lower end of said rod for reciprocation therewith and having an axial port extending therethrough, a ball valve mounted in the upper end of said plunger, and upper and lower pressure valve units in the lower end of said casing and in said casting, respectively, the upper unit opening outwardly under compression created by the upstroke of said plunger, and the lower unit opening outwardly under compression effected by the downstroke of said piston, the lower valve unit including a tubular valve casing extending diametrically of the casing to provide clearance on each side thereof for the passage of material upwardly thereby.
25. 3. In a sand pump for sanding oil wells, a tubular casing adapted to be lowered into the well, a head casting threaded onto the upper end of said casing and provided with a central bore, a plunger rod slideable in said bore for vertical reciprocation in said casing, a pump plunger secured to the lower end of said rod for reciprocation therewith and having an axial port extending therethrough, a ball valve mounted in the upper end of said plunger, and upper and lower pressure valve units in the lower end of said casing and in said casting, respectively, the upper unit opening outwardly under compression created by the upstroke of said plunger, and the lower unit opening outwardly under compression effected by the downstroke of said piston, the lower valve unit including a tubular valve casing extending diametrically of the casing to provide clearance on each side thereof for the passage of material upwardly thereby, the bore in said casting having a lower flared end, and said pump plunger being provided with a beveled part fitting into said flared end to seal said bore in the limit of upstroke movement of said plunger rod.
40. 4. A sand pump for wells, including a cylind-

ical chamber adapted to be lowered in the well, a rod extending from and reciprocable within said chamber, a reciprocable pump piston connected with said rod for slideable sealing engagement with the walls of said chamber, means providing a passageway through said piston between high and low pressure portions of said chamber, a one-way valve for closing said passageway when said piston moves toward said high pressure chamber portion, a relief valve for venting said high pressure portion of the chamber upon such movement of said piston, and a relief valve for venting said low pressure portion of the chamber upon movement of said piston in the opposite direction.

5. A sand pump for wells, including a cylindrical chamber adapted to be lowered in the well, a reciprocable rod extending through the upper end of said chamber, a piston secured to said rod for slideable sealing engagement with the walls of said chamber, means providing a passageway through said piston establishing communication between the upper and lower portions of said chamber, a one-way valve carried by said piston for closing said passageway when said piston moves toward the upper end of said chamber, a one-way relief valve at the upper end of said chamber for venting said upper chamber portion when said piston moves toward said upper end of the chamber.

30. 6. A sand pump for wells, including a cylindrical chamber adapted to be lowered in the well, a reciprocable rod extending through the upper end of said chamber, a piston secured to said rod for slideable sealing engagement with the walls of said chamber, means providing a passageway through said piston establishing communication between the upper and lower portions of said chamber, a one-way valve carried by said piston for closing said passageway when said piston moves toward the upper end of said chamber, a one-way relief valve at the upper end of said chamber for venting said upper chamber portion when said piston moves toward said upper end of the chamber, and a one-way relief valve at the lower end of said chamber for venting said lower chamber portion when said piston moves in the opposite direction.

AMBROSE L. COX.
